UNITED STATES PATENT OFFICE

2,424,010

FIELD COMPRESSOR

Farrile S. Young, Kansas City, Mo., assignor to
 Panhandle Eastern Pipe Line Company, Kansas
 City, Mo., a corporation of Delaware

Application October 12, 1944, Serial No. 558,427

5 Claims. (Cl. 230—206)

1

This invention relates to field compressors, and particularly to an oil cooling system for engines used in such compressors.

In ordinary present day practice, with field compressor stations located at the point of use, it is necessary to drill water wells for supply of water to cool the oil in the motor to prevent overheating of such motor. This is, of course, an expensive procedure and applicant's device is designed to eliminate the sinking of such water wells.

The principal objects of the present invention are to provide a portable type compressor having a symmetrical and compact arrangement of piping so that the device may be moved from one place to another and quickly and easily assembled for use; to provide a heat exchanger for cooling the oil in the motor of said compressor; to provide means for supplying gas from a source of supply to said heat exchanger for cooling the oil from the motor; to provide improved means for effecting the heat transfer between the engine oil and the cooling water; to provide means connecting the oil containing crank case and said heat exchanger; to provide means for circulating said oil through said heat exchanger, and to provide a simple and economical device capable of operating in an efficient manner for the purpose set forth.

In accomplishing these and other objects of the invention I have provided improved details of structure, the preferred form of which is illustrated in the accompanying drawing, wherein:

Fig. 1 is a perspective view illustrating my invention showing the crank case partly broken away to show the oil therein.

Fig. 2 is a longitudinal cross-sectional view through the heat exchanger forming part of my invention.

Referring more in detail to the drawing:

1 designates a field compressor embodying the features of my invention supported on a base 2. My compressor is particularly adapted to be moved from place to place and, if desired, the base 2 may be provided with devices, such as skids or the like (not shown), for moving the compressor station from one place to another or it may be placed on a truck for transportation.

3 designates an engine or motor of ordinary construction having a plurality of cylinders 4, an exhaust header 5, free air header 6 and a crank case 7 adapted to contain lubricating oil 8 for the motor. The compressor is provided with a plurality of chambers 9 having a suction header 10 and a discharge header 11 for carrying the compressed gas to a pipe line.

Preferably located at one end of the compressor is a heat exchanger 12 having one end connected to a source of gas supply through pipe 13 and the other end connected to the suction head-

er 10 by pipe 14. Connected near one end and preferably at the top of the heat exchanger 12 is a pipe 15 leading to the end of the crank case 7 and connected thereto as indicated at 16, through which hot oil from the engine is passed to the heat exchanger. Connected preferably to the top of the opposite end of the heat exchanger is a pipe 17 leading to the crank case 7 for allowing the cooled oil to flow back to the crank case after it has been passed through the heat exchanger and been cooled.

Water is circulated through the engine from a radiator (not shown) through pipe 18 to the end of the crank case as indicated at 19 and after circulating through the motor, it flows through pipe 20 back to said radiator.

I also preferably provide a fuel gas reservoir 21 having connection 22 to gas inlet pipe 13 and a pipe 23 is connected to the opposite end of said reservoir leading to said motor for supplying fuel thereto.

The heat exchanger preferably consists of a cylindrical shell 24 provided at its respective ends with heads 25 having a plurality of openings therein receiving a plurality of tubes 26 through which gas entering from pipe 13 will pass through the heat exchanger to pipe 14 and thence to said compressor chambers. The tubes 26 may be attached to the head 25 preferably by swaging or other suitable means. I also provide baffles or the like 27 in said cylindrical shell offset from each other to provide a tortuous passage for the oil passing through said heat exchanger so that the oil will be thoroughly cooled before it leaves the heat exchanger. Headers 28 and 29 are connected to the respective ends of the heat exchanger and to the inlet and outlet pipes 13 and 14 as best illustrated in Fig. 2.

Operation of a device constructed and assembled as described is as follows:

Gas may be supplied from any suitable source and passed through a scrubber (not shown). The gas enters the heat exchanger 12 through pipe 13 thence through the tubes 26 to pipe 14 connected to the opposite end of said heat exchanger and thence to the suction head above the compressor chambers 9. Gas from a source of supply, such as a gas well, usually enters the heat exchanger at a temperature from 40° to 60° F. Hot oil to be cooled will pass from the engine through pipe 15 to the heat exchanger. The oil will flow over and around the tubes 26 in the heat exchanger and the gas flowing through the tubes, being very much cooler than the hot oil coming from the engine, will reduce the temperature of the oil to approximately 100° to 120° F. After the oil has been cooled it will pass out through pipe 17 back to the crank case 7 of the engine as indicated at 30. The heat exchange is accomplished through the film of oil flowing through the

tortuous path provided by the baffles in the heat exchanger around said tubes and the cool gas passing through said tubes. After the gas is passed through the compressor 8 it is sent to a point of use through pipe 31. The fuel gas is bypassed from pipe 14 to the reservoir and thence to the engine to supply fuel for running the engine.

While I have described my particular heat exchanger as having a series of tubes extending longitudinally thereof for passage of the gas therethrough in heat exchange relation with the hot oil, it will be obvious that other means such as a coil may be used for passing the oil therethrough and flowing the gas around said coil or other means.

It will be obvious from the foregoing that I have provided improved details of structure for cooling the oil in a motor for a field compressor, one which may be run for a considerable length of time without attention, and one that can be easily and quickly transported from one place to another for use.

What I claim and desire to secure by Letters Patent is:

1. A device of the character described comprising, a compressor, a motor having a crank case containing oil for lubricating said motor, a gas supply line leading to said compressor, and means in said line for cooling said oil.

2. A device of the character described comprising, a compressor, a motor having a crank case containing oil for lubricating said motor, a gas supply line leading to said compressor, means in said line for cooling said oil, and means for returning said oil to said motor.

3. A device of the character described compris-

ing, a compressor, a motor having a crank case containing oil for lubricating said motor, a gas supply line leading to said compressor, a heat exchanger in said line for cooling said oil, and means for returning said oil to said motor.

4. An apparatus of the character described comprising, a compressor, a motor having a crank case for containing oil for lubricating said motor, a gas supply line leading to said compressor, a heat exchanger in said line, and means for passing said oil from said motor through said heat exchanger in heat exchange relation with said gas for cooling said oil.

5. An apparatus of the character described comprising, a compressor, a motor having a crank case for containing oil for lubricating said motor, a gas supply line leading to said compressor, a heat exchanger in said line, means for passing said oil from said motor through said heat exchanger in heat exchange relation with said gas for cooling said oil and returning said cooled oil to said crank case.
